UNITED STATES PATENT OFFICE.

PETER LORD, OF MONTREAL, QUEBEC, CANADA, ASSIGNOR OF ONE-FOURTH TO JOSEPH ANTOINE HILAIRE HEBERT, ONE-EIGHTH TO GUSTAVE ITZWEIRE, AND ONE-EIGHTH TO LOUIS ADHEMAR DELORME, ALL OF MONTREAL, CANADA.

VALVE.

1,041,123.

Specification of Letters Patent. — Patented Oct. 15, 1912.

Application filed September 19, 1911. Serial No. 650,239.

To all whom it may concern:

Be it known that I, PETER LORD, resident of the city and district of Montreal, Province of Quebec, Dominion of Canada, a subject of the King of Great Britain, have invented certain new and useful Improvements in Valves; and I do hereby declare that the following is a full, clear, and exact description of the same.

10 The invention relates to improvements in valves, as described in the present specification and illustrated in the accompanying drawings that form part of the same.

15 The invention consists essentially in the novel means employed whereby the valve is held fluid tight in its closed position by metal to metal joints.

20 The objects of the invention are to devise a valve which will entirely obviate the necessity of any form of replaceable packing, to form the valve entirely of permanent pieces, and generally to provide in such devices a construction which will be cheap to manufacture and economical in regard to its 25 maintenance.

25 In the drawings, Figure 1 is a vertical sectional view of this form of valve, applied to a globe valve of a heating system. Fig. 2 is a cross sectional view on the line C—D in Fig. 1. Fig. 3 is a cross sectional view on the line A—B in Fig. 1. Fig. 4 is a vertical section of this valve applied to a faucet and showing the valve in modified form which may also be applied to the globe casing of a valve and heating system.

30 Like numerals of reference indicate corresponding parts in each figure.

35 Referring to the drawings, 1 is the valve casing, here shown as of globe form, though it must be understood that this casing may be of any suitable shape, according to the circumstances under which the valve is used, said valve casing having the internal threaded neck 2 extending outwardly therefrom, 40 said neck terminating in the flange 3, the flange being surface finished.

45 4 is the valve seat, formed by the sloping wall of the inwardly extending annular par-

50 tition 5 intermediate of the height of said valve casing 1, said partition extending downwardly from said seat and having the straight wall 6 forming a guide, this guide may form part of said partition or may be a separate ring inserted therein rigidly held.

55 7 is a disk or plate valve having the inwardly inclined surface 8 engaging the valve seat 4 in the closed position of the valve and the boss 9 extending upwardly from the center thereof and terminating in the ball 10.

60 11 is a spider secured to the inner side of the valve 7 and having the straight legs 12 engaging the guide wall 6 and thus avoiding the upsetting of the valve 7.

65 13 is a barrel casing, having the outwardly extending flange 14 toward the lower end thereof, the external thread 15 below said flange and corresponding to the internal thread of the neck 2 and inserted therein and the internal thread 16 for the greater portion of its length, said flange 14 being 70 surface finished and meeting the surface finished face of the flange 3.

75 17 is the reduced upper end of the barrel casing 13 formed by the squared inwardly extending shoulder 18, said reduced end on the top side being surface finished and said shoulder 18 on the inside being surface finished. It will be thus seen that the barrel casing 13 forms an entrance to the globe casing 1, the surface finished flanges 3 and 14 80 preventing any leakage at that joint.

85 19 is a plug, having the ball shaped recess 20 at the lower end thereof, corresponding to the ball 10 and into which said ball fits, being held therein by the flange 21 extending below said plug, said plug having at the other end thereof a squared recess 22. The plug 19 is threaded correspondingly at 23 to the internal thread of the barrel casing 13 and turns therewithin. The ball 10 of 90 the valve 7 is inserted in the recess 20 and the flange 21 is knocked over under the inward curve of the said ball 10, so that the said ball is held within the globe shaped recess and the valve 7 is consequently carried 95 with the plug 19 during the travel of said

plug, and a universal joint is secured between said plug and said valve by the insertion of said ball in said recess.

The valve 7 on its outer face, preferably 5 has a squared recess 24, opposite a threaded opening 25 in the valve casing, but said threaded opening 25 is closed by the threaded plug 26 so that by means of this opening in the squared recess the valve face engaging 10 the seat 4 may at any time be ground perfectly with said seat, simply by introducing some emery dust or other suitable grinding material and opening the hole 25 and then inserting a squared piece in the 15 squared recess 24 of the valve and turning said valve, either by hand, brace-bit or other instrument.

27 is a spindle having the flange 28 at the lower end thereof said flange having an 20 inclined upper surface corresponding to the inclined shoulder 18 and an annular recess 28^a in said inclined surface forming a double seat. 29 is a squared pin projecting centrally from said flange 28 into the 25 squared recess 22 in the plugs 19.

30 is a flattened surface in the length of spindle above the flange 28. 31 is a thread formed on said spindle above said flattened surface.

30 32 is a hand wheel at the upper end of the spindle 27.

The spindle 27 is inserted through the reduced end 17 of the barrel casing 13 so that the surface finished face of the flange 28 35 comes in contact with the surface finished face of the shoulder 18.

33 is a washer, having a part circular hole therethrough, the straight wall of said hole engaging the flat surface 30 of the spindle 27 and the inner end of said washer being surface finished and engaging the surface finished top of the reduced end 17. 34 is a nut mounted on the spindle 27 and engaging the thread 31 and tightly securing 45 said washer 33 against the top of the reduced end 17.

In the operation of this invention, the valve is placed in any suitable position, according to the conditions under which it is 50 being used, as it may be a faucet or an attachment to a heating system, in fact it is useful any place where a fluid valve can be operated, the only change necessary being in the arrangement of the casings. The 55 fluid in the open position of the valve passes through the opening surrounded by the valve seat 4 and then through various connecting pipes. In order to close this valve, the wheel 32 is turned, or other handle, and 60 the spindle turns with said wheel and rotates in the journal bearing formed by the reduced end 17. The squared pin 29, extending down into the plug 19, causes said plug to turn and as this plug screws up

and down within the barrel casing 13, according to the number of turns given the hand wheel, the valve 7 is moved correspondingly, for by its universal joint connection with the said plug, it is bound to follow the movements thereof. The spider 70 guide 11 extending from the valve directs it properly to its seat so that it cannot go through the valve opening in an upset position.

The joints between the washer and the 75 upper end of the barrel casing and between the barrel casing and the valve casing, as well as the joint between the spindle flange and the inner wall of the barrel casing, absolutely preclude any chance of a leakage 80 through those parts, therefore the necessity for washers of other material softer than the metal of the valve parts is entirely avoided.

In Fig. 4, the valve shown is applied to 85 a faucet and is in slightly different arrangement, in fact it is another form of the same invention and this form may just as easily be applied elsewhere as to a faucet. 35 is a threaded opening into the tap casing 90 corresponding to the threaded opening into the aforesaid globe casing. 36 is the plug casing corresponding to the aforesaid barrel casing and having a similar flange 37 meeting the top of the wall of the opening 95 35 and the internal thread 38, said plug casing 36 having the inclined wall 39 intermediate of its length converging to the reduced upper end 40. 41 is a similar plug to that described hereinbefore and turning 100 105 in the thread 38. 42 is a spindle inserted through the reduced upper end 40 and having the flange 43 at the lower end thereof annularly recessed at 44 forming the seats 45 and 46 against the surface finished inner wall of the incline 39. 47 is a squared portion near the top end of the spindle 42 inserted through a squared hole in the lever 48, said spindle terminating at its extreme upper end in the thread 49. 50 is a washer 110 between the lever 48 and the top end of the reduced upper end 40. 51 is a split nut, screwing on to the thread 49 and tightened against the lever 48 being held in place by the set screw 52 inserted through the extending split lugs 53. This is a common 115 form of nut and in itself is not claimed as novel herein but in the operation of this form of the invention the lever 48 is turned which turns the plug 41 and causes said 120 plug to travel up and down in the casing 36, thus lifting the valve from its seat in the tap casing. The flange 43 is drawn to the inner wall of the inclined shoulder by tightening the split nut 51 against the lever 125 or wheel 48, thus providing an extremely simple method of holding the upper portions of the device liquid tight.

What I claim as my invention is:

1. In a valve, a casing having a valve seat formed therein, a valve resting on said seat and having a central boss terminating in a ball, an extension screwed into said casing and forming therewith a metal to metal joint, a plug screwing longitudinally in said extension and having a ball cavity at the lower end thereof and partially inclosing said ball, a stem projecting into said extension and into said plug and journaled at the outer end of said extension and having a flange forming with the wall of said extension a metal to metal joint, a washer 10 encircling said stem and non-rotatively secured thereon and forming with the end of said extension a metal to metal joint, and a nut locking said washer.
2. In a valve, a casing having a partition 20 therein with a central opening and sloping walls at the edge of said opening, a correspondingly formed disk or plate valve fitting to and closing said opening and having a central boss terminating in a ball, an extension screwing into said casing and forming therewith a metal to metal joint and threaded in the interior thereof, a plug correspondingly threaded and screwing in said extension having a square recess at one end 30 thereof and a ball cavity in the other partially inclosing said ball, a stem journaled at the outer end of said extension having a flange toward the inner end thereof forming with said extension a metal to metal joint and a square pin projecting from said flanged portion into said plug, a washer non-rotatively arranged on said stem and forming with the end of said extension a metal to metal joint, and a nut screwing on said 40 stem against said washer.
3. In a valve, a casing having a partition 45 therein and an opening through said partition, said partition having a sloping wall at the edge of said opening and forming a valve seat, a valve fitting to and closing said opening having a central boss terminating in a ball, an extension screwing into said casing and having a flange, forming with said casing a metal to metal joint, and an 50 internal thread, a plug correspondingly threaded and screwing longitudinally in said extension and having at one end thereof a squared recess and at the other end a ball cavity and flange adapted to be knocked 55 over and partially inclose said ball in said cavity, a stem journaled at the outer end of said extension and having a flange forming with the interior wall of said extension a metal to metal joint, a square pin project- 60 ing from said flange into said squared recess in the plug and a flattened side beyond said extension, a washer having a corresponding opening therethrough and fitting on said stem at said flattened part and forming with the outer end of said extension a metal to metal joint, and a nut screwing on said stem and holding said washer.
4. In a valve, a casing having a partition 65 wall therein and an opening through said partition, said opening having sloping walls 70 forming a valve seat and straight walls leading from said sloping walls, a valve fitting to and closing said opening and having at one side guide legs engaging said straight walls and on the other side a central boss 75 terminating in a ball, an extension screwing into said casing and having a flange forming with said casing a metal to metal joint and an internal thread, a plug screwing in said extension having at one end a squared 80 recess and at the other end a ball cavity partially inclosing said ball, a stem having a square pin projecting into said squared recess, a flange forming with the interior wall of said casing a metal to metal joint and a 85 flattened side beyond said extension, a washer fitting to said flattened side and forming with said casing a metal to metal joint, and a nut holding said washer in 90 place.
5. In a valve, a casing having a partition and an opening through said partition and sloping walls at said opening forming a valve seat, a valve fitting to and closing said opening and having on one side a spider 95 with straight legs forming guides and at the other side a boss terminating in a ball, guide walls rigid with said partition and engaged by said straight legs, an extension screwing into said casing and having a flange intermediate of the length thereof forming with said casing a metal to metal joint and an internal thread, a plug having a corresponding thread and screwing in said extension 100 and also having a squared recess at one end 105 and a ball cavity at the other partially inclosing said ball, said extension having a reduced end forming a shoulder with a surface finished inner side and surface finished at the ends, said reduced end forming the 110 bearing, a stem journaled in said bearing and having a flange extending outwardly therefrom with a surface finished face engaging the inner side of said shoulder, a square pin projecting from said flange into 115 said plug and a flat face on one side beyond said extension, a washer having a corresponding opening fitting on said stem at its flattened part and having a surface finished face engaging said reduced end, and a nut 120 screwing on said stem and engaging said washer.
6. In a valve, a casing having a valve seat therein and an opening in vertical alignment with and below said valve seat, a plug 125 closing said opening, a valve fitting on to said valve seat and having on one side a central boss terminating in a ball and on

the other side a square recess, a hollow barrel portion screwing into said casing on the opposite side of said valve to the opening aforesaid, a plug having a ball cavity at 5 one end engaging said valve ball and operating in said barrel portion, a stem journaled at the outer end of said barrel portion in axial alinement and operatively connected with said latter plug and having an in- 10 tegral, surface-finished lower end directly

contacting an integral roofed part of said barrel portion in a fluid tight metal to metal joint.

Signed at Montreal, Quebec, Canada, this ninth day of September, 1911.
